Primary Examiner — T Chase Nelson

Assistant Examiner — Sydney Margaret Parsley

(57) **CLAIM**

The ornamental design for a shed, as shown and described.

DESCRIPTION

1. Shed

1.1 : Perspective

1.2 : Perspective

1.3 : Front

1.4 : Back

1.5 : Left

1.6 : Right

1.7 : Top

1.8 : Bottom

1.9 : Enlarged

1.10 : Enlarged

1.11 : Enlarged

The parts shown by means of broken lines in the reproductions are not part of the claimed design; fig. 1.9 is the enlarged view of the portion taken at line 1.9 in fig. 1.1; figs. 1.10, 1.11 are the enlarged views of the portion taken at line 1.10, 1.11 in fig. 1.2; the dash dot dash broken lines in the reproductions represent boundaries for the enlarged views and form no part of the claimed design.

1 Claim, 11 Drawing Sheets# US D1,038,440 S
